UNITED STATES PATENT OFFICE.

ALPHONS LOETSCHERT, OF HÖHR, GERMANY.

DESIGN FOR A PITCHER OR TANKARD.

SPECIFICATION forming part of Design No. 30,978, dated June 13, 1899.

Application filed February 16, 1899. Serial No. 705,727. Term of patent 3½ years.

To all whom it may concern:

Be it known that I, ALPHONS LOETSCHERT, a subject of the German Emperor, and a resident of Höhr, near Coblenz, in the Kingdom of Prussia, German Empire, have invented a new and original Design for a Pitcher or Tankard, of which the following is a specification.

My design consists of a tankard or pitcher in the form of a human head *a* and neck *d*, the neck forming the base of the tankard and the crown *b* forming the cover, there being a line of division running horizontally between the crown and main part of the head.

From the crown an extension *x* projects rearwardly, while from the base of the neck in the

rear a curved handle *c* extends and is joined to the back part of the head, and this handle has a portion connected with the rear extension *x*, the latter having a projection *y*. The top of the head is surmounted by a wreath *z* and a band or crown *3*.

I claim—

The design for a pitcher or tankard herein shown and described.

In witness whereof I have hereunto set my hand in presence of two witnesses.

ALPHONS LOETSCHERT.

Witnesses:

PAUL HASCOW,
LUDWIG FEURER.
